(54) **SILVERING & GILDING LEATHER**

(76) Inventor: **Levi Kenton**

Lori, Henton of Philadelphia, Pennsylvania
Letters Patent.

The Schedule referred to in these Letters Patent and making part of the same, containing a description in the words of the said Lori Henton himself of his Improvement in the Art of Gilding and Bedding Leather.

To all to whom these presents shall come. Be it known that I Lori Henton of the City of Philadelphia and State of Pennsylvania, have invented a new and useful improvement in the art of gilding and bedding leather, and that the following is a full and exact description of the process and composition of matter employed therein as invented by me. The composition of matter, or size, rendering the leaf adhesive is thus prepared. Reduce half a pound of Ivory turnings (fish, glue or isinglass) added to two quarts of water, to one pint by boiling. Thus reduced the composition is strained through linen or muslin, and a single coat is laid on the leather with a sponge and dried, or instead of this composition lay on two coats of the whites of eggs, and dry it in the same manner. The leather is then softened by a coat of tallow mixed with sweet oil. The gold or silver leaf is then laid on oot of the book or with the ordinary tip used by Gilders. It is then run, or passed through two rollers, fashioned according to the shape intended for the leather, and heated as they usually are for the purpose of embossing leather, after running it through the rollers, the loose leaf is removed by wiping it with a cotton rag. It is then carefully rubbed with a white handkerchief taking care not to injure the impression. This completes a glop to the coloured portion of the leather and completes the process. The leather may be of Goat, Sheep, or Calf, Skin, & of any colour cut previously to any required size. If fish glue or Isinglass be used in lieu of Ivory turnings, one ounce of either dissolved by immersing it in a pint of water is sufficient.
